UNITED STATES PATENT OFFICE.

LEIGHTON N. D. MIXSELL, OF BETHLEHEM, PENNSYLVANIA, ASSIGNOR TO BETHLEHEM STEEL COMPANY, OF SOUTH BETHLEHEM, PENNSYLVANIA, A CORPORATION OF PENNSYLVANIA.

METHOD OF MAKING EXPLOSIVE PROJECTILES.

1,162,183.

Specification of Letters Patent. Patented Nov. 30, 1915.

Application filed March 2, 1915. Serial No. 11,503.

To all whom it may concern:

Be it known that I, LEIGHTON N. D. MIXSELL, a citizen of the United States, residing at Bethlehem, county of Northampton, 5 State of Pennsylvania, have invented certain new and useful Improvements in Methods of Making Explosive Projectiles, of which the following is a specification.

Explosive projectiles are usually provided 10 with a cavity for the bursting charge which is generally cylindrical, though sometimes slightly tapering, the forward end of the cavity being shaped to conform more or less to the contour of the point of the projectile 15 and the rear end being narrowed to a neck which receives the base plug or fuse. On account of operating the boring tools through the comparatively narrow fuse opening in the base of the projectile it has 20 been more or less difficult and somewhat expensive to bore out the cavity and troublesome to properly shape the forward end thereof. To obviate these difficulties I have invented the following described method of 25 making projectiles, particularly cast steel projectiles.

I first cast a solid projectile blank having an annular outwardly extending flange or "boss" at its base. As is well known, the 30 impurities in the metal and any spongy formations due to gases occur at the middle of the casting and are removed in boring. I then bore out the cavity for the proposed charge, this opening extending through the 35 base and centrally through the projectile to the point where the tapering end of the cavity begins. Through this opening a suitable tool may be inserted for shaping the inner end of the cavity. I then partially 40 close the outer or base end of the cavity by swaging or pressing inward the annular enlargement, thus forming a neck to receive the fuse plug or other closure. This neck is finally threaded and shaped to receive the 45 closure.

My improved method is illustrated in the accompanying drawing, in which,

Figure 1 is a longitudinal section of a solid or blank projectile; Fig. 2 is a similar 50 section showing the blank after the boring is completed; Fig. 3 shows the projectile after the surplus metal on the base has been pressed or swaged inwardly to form the

base of the projectile and produce a neck in the cavity to receive the plug; Fig. 4 55 shows a shell with its base threaded to receive the fuse or other closure.

In Fig. 1 I have shown a solid blank which may be assumed to be a steel casting having the usual outline of a projectile comprising a curved point 10 and a cylindrical body 11 and having at its base an annular enlargement 12 for a purpose to be presently described. A longitudinal bore 13 is first formed in the shell, as indicated in Fig. 2, 60 the diameter of this bore being equal to the diameter of the required cavity for the bursting charge. This bore or cavity may be of uniform diameter from the base inward to a point 14 and from this point 65 rounded or conical, as shown, or it may be of any other desired shape.

After boring the cavity the base of the projectile is heated sufficiently to soften the metal and the outwardly projecting flange 75 12 is pressed radially inward to form an internal annular flange 15, as illustrated in Fig. 3. This operation is performed by suitable dies or devices which leave the outer surface of the base cylindrical and of substantially the same diameter as the body of the projectile. The projectile is finally 80 threaded or tapped, as indicated at 16, to receive a base plug or fuse. The outer portion of the projectile may be finished with 85 the usual copper band, or in any other desired way.

It will be evident that it is very much easier to bore the cavity shown in Fig. 2 of full size from the base inward than to bore 90 a cavity such as shown in Fig. 3 with a contracted opening in the base through which the boring tools must operate. It will also be evident that it is very much easier and cheaper to form the conical end 95 of the opening when the base is open, as shown in Fig. 2, than to form it with a partially closed base, as shown in Fig. 3. In fact a special tool or reamer adapted to finish the inner end of the cavity can be 100 readily inserted and operated in the form shown in Fig. 2 while a reamer of this construction could not be inserted into the cavity shown in Fig. 3. My improved method of manufacturing projectiles therefore effects a considerable saving in labor 105

and allows of the use of simpler forms of tools.

Having thus described the invention, what is claimed and desired to be secured by Letters Patent is:

1. The method of making a projectile which consists in forming a solid blank having a cylindrical body portion and an annular enlargement at its base, then boring 10 through the base and forming the cavity in the body of the projectile, and then pressing the metal of the base radially inward to form an inwardly turned flange to receive the base plug or fuse.
- 15 2. The method of making a projectile which consists in forming a blank having the usual cylindrical body and tapering point and having an annular enlargement at its base, then boring through the base to 20 produce a cavity for the bursting charge, then heating and pressing inward the enlargement at the base to reduce the diameter of the base to substantially that of the

body and form an inwardly turned flange to receive the base plug or fuse.

3. The method of making a projectile which consists in forming a solid blank having the usual cylindrical body and tapering point and having an annular enlargement at its base, boring an opening through 30 the base and body, to produce a cavity for the bursting charge, completing said cavity to a rounded or tapering point within the point of the projectile, then heating and pressing inward the enlargement at the base 35 to contract the bore, and finally finishing the contracted portion of the bore to receive the base fuse or plug which closes the shell cavity.

In testimony whereof I affix my signature 40 in presence of two witnesses.

LEIGHTON N. D. MIXSELL.
